GRANULAR STOCK VACUUM-DRIER
PNEUMATIC LOCK CONTROLRudolf Dumermuth, Uzwil, Switzerland, assignor
to Gebrüder Bühler, Uzwil, Switzerland

Application October 23, 1950, Serial No. 191,571

Claims priority, application Switzerland
October 27, 1949

7 Claims. (Cl. 214—17)

1

In vacuum dryers locks in form of valves serving for the passage of goods to be treated, such as grain, corn, rapeseed, hazelnuts and the like, have been mechanically controlled up to the present.

In contrast thereto, the locks according to my present invention are pneumatically controlled in accordance with a predetermined operating program, for which purpose there are suitably provided pistons acting as reversing slides and check valves associated therewith.

Such a pneumatic control system, as compared with a mechanical control system, is cheaper in manufacture and affords a more reliable operation.

An example of my present invention as applied to a vacuum dryer, is shown in the accompanying, partly schematical drawings, in which:

Fig. 1 is a vertical section through the vacuum dryer,

Fig. 2 is an elevation, in a larger scale, of a dried-goods discharge mechanism associated with the drying chamber,

Fig. 3 is an elevation seen at right angles to that shown in Fig. 2,

Fig. 4 is a plan view of Fig. 3, partly in section,

Figs. 5 and 5a is a vertical section, in a larger scale, through the vacuum-dryer inlet and a schematical view of parts of a control apparatus,

Fig. 6 shows a vertical section through the control apparatus,

Fig. 7 shows a detail of Figs. 5a and 6 in a larger scale, namely a check valve, and

Fig. 8 shows a further detail, also in a larger scale, namely a venting valve.

The dryer comprises a relatively tall cylindrical jacket 1 (shown broken away in Fig. 1) in which is disposed a heating device of rectangular cross-section. The said device, as known in the art, comprises a tube system of tubes 2 which are oval in cross-section and through which steam is fed during operation of the dryer. The jacket 1 has frusto-conical top and bottom portions 3 and 4 connected to the inlet and outlet respectively. The inlet and outlet each comprises two superposed lock chambers 5, 6 and 7, 8 respectively, these four chambers being coaxial with jacket 1. At the points of transition from the top chamber 5 to chamber 6 and from the latter to a chamber 9 formed by the conical top portion 3, a conical lock valve 10 and 11 respectively, is disposed. The chamber 9 which borders the drying space 12 on top, is bound at the bottom by a frusto-conical funnel 13 which is connected to the heating system 2. At the lower end of space 12 there is disposed a dis-

2

charge mechanism comprising four hoppers 14 of which each terminates in a spout 15 to which a closure rocker 16 is associated. The rockers 16 are secured in pairs to a common shaft 17, and the two shafts 17 are journaled in drop hangers 18 suspended from the hoppers 14. The two shafts 17 are coupled with the aid of shear means 19 of which the arms are interconnected by a pin 20 which is provided with a nut, so as to be capable of simultaneously performing a limited rocking movement. The shaft 17 shown on the left in Figs. 3 and 4 has an extension to which is secured a telescoping rod 21 which is connected to a rod 22 of a working piston disposed in a control cylinder 23. The spouts 15 extend downwardly into the lock chamber 7 which is bound by the lower frusto-conical portion 4. A conical lock valve 24 is disposed intermediary of chamber 7 and the lower lock chamber 8. Another conical lock valve 25 is provided between the chamber 8 and a bottom hopper 26 which terminates in a discharge spout.

The lock valves 10, 11, 24 and 25 are pneumatically actuated, as will be later explained in detail, as is also the piston provided in the control cylinder 23 for moving the shaft pair 17 which controls the rockers 16. A shutter 27 is also pneumatically actuated and controls an inlet spout 28 associated with the topmost lock chamber 5. The shutter 27 is pivoted on a pin 29 to the spout 28 and connected to the rod 30 of a working piston 32 (Fig. 5) which is disposed in a control cylinder 31. The latter is pivoted at 33 to a cover cylinder 34 which in turn is pivoted at 33 to a cover 34 of lock chamber 5; if desired the cover 34 may be omitted.

The goods to be treated are fed in any convenient way, e. g. mechanically or pneumatically, to the inlet spout 28. When the shutter is swung away from the mouth of spout 28, the goods are delivered into the lock chamber 5. With the shutter 27 in closing position and the valve 10 in the open position, the goods pass from chamber 5 into the chamber 6 and thence—with lock valve 10 closed and lock valve 11 open—into the chamber 9 and, thus, into the drying space 12. The lock valve 11 then is closed again. The goods, having passed the space 12 (which is filled with goods at all times), is fed through the hoppers 14 and the spouts 15 to the rockers 16 whence, when the latter are swung away from the spouts 15, the goods dribble into the lock chamber 7. With the rockers 16 in closing position and the chamber 8 having been evacuated, the goods pass from the chamber 7 into the chamber 8, by opening the lock valve 24, and

thence into the hopper 26, the lock valve 24 having been closed air admitted into the chamber 9 and the valve 25 opened. The dried goods then pass from space 26 to another treatment station, e. g. to a recooler. The operation described is repeated so long as the lock chamber 5 provided in the inlet path of the dryer, is fed with goods.

The four lock valves 10, 11, 24 and 25 associated with the lock chambers are actuated, as required, by a working piston each, the said pistons being disposed in stationary control cylinders 35-38 respectively.

The control cylinders 35-38, as well as the above mentioned control cylinders 31 and 23, are connected to a control apparatus by two pipes each. The control apparatus is shown in Figs. 5a and 7, and comprises a camshaft 40 having cams 39 fixed thereto. The shaft 40 is driven through a chain drive 41 from an electric motor 42, suitably via a reducing gear associated with the latter. A bell crank 44 pivoted at 45 and loaded by a spring 43 (Figs. 6, 7) coacts with each cam 39 and, by means of an extension 46, is connected to a pin 47 of a check valve 48 disposed in a cylinder 49 which comprises the valve seat. All the valve cylinders 49, as shown in Fig. 5a are mounted on a common beam 50. Each cylinder 49 through a tube 51 is connected to a fixed cylindrical casing 52 containing a reversing piston 53 loaded by a spring 54 and having a peripheral groove 55 and a stop projection 53. A branch tube 57 from a header 56 opens into each casing 52. The tube 57 also communicates with casing 52 through a bend 58 which contains a point of passage of extreme constriction 83. The header 56 is connected to a compressor or pneumatic means indicated by 56a in Fig. 5a (not shown in detail).

In Fig. 5a eight reversing stations I-VIII are shown, the casing 52 of each of which is connected to a valve cylinder 49 through a tube 51. A tube 59 is connected to each casing 52 and communicates with the peripheral groove 55 of the piston 53. When the piston 53 is moved to the right the tube 59 further communicates through bores 81 and 82 in the casing 52 with the atmosphere. From casing 52 of reversing station I a tube 59, 60 extends to the control cylinder 31 (Fig. 5) which through a tube 61 also is connected to the tube 59 issuing from casing 52 of the reversing station II. The two tubes 59 springing from the casings 52 of two reversing stations III and IV communicate with the control cylinder 35 through two additional tubes 62 and 63. The control cylinder 36 through two additional tubes 64 and 65 is connected to the two tubes 59 of the casings 52 associated with the reversing stations V and VI. The two tubes 59 of the casings 52 associated with the reversing stations VII and VIII communicate with a vent valve 68 (Figs. 5 and 8) through two additional tubes 66 and 67. The valve 68 through a tube 69 is connected to the lock chamber 6, through a tube 70 to a vacuum pump but indicated at 70a in Fig. 5 (not shown in detail) and through a tube 71 communicates with the atmosphere. The vent valve 68, as shown in Fig. 8, is provided with two spring-loaded valves 72 and 73 of which the former is associated with tube 70, and the latter with tube 71.

In a manner similar to that of the control cylinders 35 and 36 of the lock valves 10 and 11, the control cylinders 37 and 38 (Fig. 1) of the lock valves 24 and 25 are connected through two conduits 74, 75 and 76, 77 to two separate (not shown)

control casings 52 of the control apparatus. The lock chamber 8 through a conduit 78 communicates with a separate venting means 68 of the kind described which also through two conduits 5 is connected to two separate control casings 52 of the control apparatus, and which also comprises a conduit leading to the vacuum pump and another conduit leading to the atmosphere. Aside of the control cylinders 35-38 of the lock valves 10, 11, 24 and 25, two conduits denoted by 79 and 80 are associated with the control cylinder 23 which is provided for the discharge device 14, and so on, of the drying space 12, which conduits 79 and 80 are connected to two separate control casings 52 of the control apparatus.

Before taking in operation the dryer compressed air is passed from the compressor through header 56 to the control apparatus. The cam-shaft 40 is driven through motor 42 via chain drive 41, whereby the check valves 48 (Fig. 7) disposed in the cylinder 49 are periodically opened and closed through the cams 39 in a given operating sequence. Assuming that the check valve (48) disposed in the cylinder 49 farthest to the left in Fig. 5a is closed, the following operations will take place:

The air flowing from header 56 through branch conduit 57 and bend 58 into casing 52 of the reversing station I moves the piston 53 (Fig. 6) rearwardly against the force of spring 54. When the piston has covered a certain distance of its stroke, the annular peripheral groove 55 thereof establishes communication with the conduit 59 issuing from casing 52, whereupon the air is led through conduit 59 and the connected additional conduit 60 to control cylinder 31, and the shutter 27 of inlet spout 28 is swung into the open position through the piston 32 of cylinder 31, the valve 10 of lock chamber 5 being in the closed position. The air expelled from control cylinder 31 owing to the movement of piston 32, escapes to the atmosphere through the conduits 61, 59, connected to the casing 52 of reversing station II and the bores 81 and 82 of the casing 52 the piston 53 of this station has been moved to the right. After the lock chamber has been charged with goods, that check valve 48 is opened through the respective cam 39, which is disposed in the particular cylinder 49 associated with the reversing station I. In the appurtenant casing 52, therefore, the air-pressure is reduced, and its piston 53 is removed by spring 54 to the right into the initial position, thus the upper room of the control cylinder 31 is connected to atmosphere through the conduits 60, 59 and the bores 81, 82 of the casing 52 of reversing station I. Moreover, the second check valve 48 from left is closed through the respective cam 39 which is disposed in the particular cylinder 49 associated with the reversing station II. Air thus is fed into control cylinder 31 through the respective conduits 59 and 61 and, therefore, the piston 32 in cylinder 31 is moved in such direction that shutter 27 will close the inlet spout 28. The air expelled from control cylinder 31 escapes to the atmosphere as described before. By reason of the fact that the bend 58 connected to conduit 57 has a constricted flow-aperture 83, the rate of air flowing from conduit 57 through an open check valve is only small and, thus, is not detrimental in any way.

After a certain amount of goods has accumulated on top of lock valve 10 of the upper lock chamber 5, the lock valve 10 is temporarily opened, namely by means of the piston provided in control cylinder 35 in that air is fed into the

latter through the conduits 63 and 62, which takes place through the casings 52 of the reversing stations IV and III respectively. The function of the pistons (54) of these control casings 52 and that of the check valves (48) in the appurtenant cylinders 49 is similar to that of the corresponding elements as described with reference to the reversing stations II and I for the control cylinder 31. After the lock chamber 6 has been supplied with goods and the lock valve 10 closed, air is evacuated from chamber 6 by the said vacuum pump, in order to balance the pressures in chamber 6 and drying chamber 12, as will be explained later. The lock valve 11 afterwards is temporarily opened, in the same manner as lock valve 10 above, from its control cylinder 36 and the two appurtenant casings 52 of the reversing stations VI and V, in order to let the goods pass from lock chamber 6 into chamber 9 from which they move to the drying space 12 which remains filled at all times. Below, the goods are in the hoppers 14, spouts 15 and on the rockers 16. The latter temporarily are swung into the open position by the action of the piston in control cylinder 23, likewise via control casings 52 or reversing stations respectively, provided on the control apparatus and having two appurtenant cylinders 49 with check valves. Following the chamber 7, the chamber 8 is fed with dribbling goods, whence—as will be explained later—air is evacuated by means of the vacuum pump 70a, Fig. 5, in order to establish balanced pressures in the chambers 8 and 12. The valve 24 then is temporarily opened in order to let pass the goods from lock chamber 7 into chamber 8. Then air is again admitted into the chamber 8 and the goods are conducted to the hopper 26 by temporarily opening the valve 25. The consecutive actuation of the two valves 23 and 25 is done, in a manner analogous to that of the lock valves 10 and 11, through the control cylinders 37 and 38 from the control apparatus via appurtenant control cases 52 and valve cylinders 49.

Before the lock chamber 6 is evacuated, the appurtenant venting means 68 is in the condition shown in Fig. 8, the chamber 6 communicating with the atmosphere through conduit 69, venting means 68 and conduit 71. In order to evacuate the said chamber 6, the control apparatus causes compressed air to flow into the vent means 68 via the conduit 67 whereby the valve 73 is urged on to its conical seat and the conduit 69 is shut off from the atmosphere. On the other hand, compressed air may escape from conduit 66 of the vent means to the atmosphere through the appurtenant control casing 52 by opening the check valve 49, whereby the valve 72 on account of being spring-loaded, is opened, whereupon air is sucked off by the vacuum pump through conduit 70 and, therefore, the chamber 6 is evacuated through the conduit 69. After the goods have dribbled into the chamber 9 due to lock valve 11 having been temporarily opened, the condition indicated in Fig. 8 is reestablished in the venting means 68, the lock valve 11 having been closed. For such purpose, the control apparatus operates to feed compressed air through conduit 66 to venting means 68 to close valve 72, while compressed air escapes from conduit 67 of the venting means 68 through the associated control casing 52 by opening the check valve 49. The valve 73 thus is opened by spring action, whereupon the lock chamber 6 through conduits 69 and 71 is connected to the atmosphere.

In a manner analogous to that described, the lock chamber 8 is temporarily vented through the conduit 78 and the venting means connected thereto.

5 The outlet spouts 15 on the hoppers 14 of the discharge device are vertically adjustable by clamping means, thus permitting to regulate the amount of goods accumulating in the chamber 7. The charge for the lock chamber 5 may be regulated in a similar manner in that the inlet spout 29 and its shutter 27 are mounted vertically adjustable on the cover 34 of chamber 5.

10 The check valves 49 may be opened by electromagnetic means instead of by mechanical means, or by any other exterior force. If desired, the locks may be constituted by elements of another character than by valves of the type described. Furthermore goods other than those capable of dribbling may enter into consideration for being 15 passed through the locks.

20 The control system disclosed by my present invention may also be applied to devices serving for grain conditioning.

What I claim as new, is:

25 1. In a granular stock vacuum-dryer pneumatic lock control, a plurality of independently operative lock chambers for the purpose of passing goods therethrough, a valve for closing and opening each lock chamber, a plurality of fixed 30 cylinders, one for each lock chamber, a movable piston in each cylinder acting as a reversing slide, a check valve associated with each piston, each cylinder having a connection running to said valve, pneumatic means for operating each piston and check valve and each lock valve, and mechanical means for operating said pneumatic means, operative in a predetermined sequence, in order to operate said pistons in said sequence, and open or close said lock.

35 2. The structure of claim 1, in which the lock chambers are closed or opened by lock chamber valves.

40 3. The structure of claim 1, in which the pistons are moved by compressed air in one direction, and by spring action in the other direction.

45 4. The structure of claim 1, in which the lock chambers are closed or opened by valves, and vent means are adapted to co-act with the said pistons and lock chamber valves so as to temporarily evacuate some of the lock chambers.

50 5. The structure of claim 1, in which the lock chambers are closed or opened by valves, and in which two pistons and two check valves are associated with each lock chamber.

55 6. The structure of claim 1, in which vent means are provided, and two pistons and two check valves associated with each vent means.

60 7. The structure of claim 1, in which vent means are provided, and said lock chambers and lock chamber valves and vent means are adapted to co-act with the said pistons and lock chamber valves so as to temporarily vent some of the lock chambers, a vacuum pump, each vent means having two valves which alternately are closed 65 by the action of compressed air and opened by spring force in order to connect the respective lock chamber alternately with said vacuum pump and with the outside atmosphere.
